LIQUID DISPENSING APPARATUS.

Thomas L. Titus, Denver, Colo., assignor to The Wyott Manufacturing Company, Cheyenne, Wyo., a corporation of Wyoming

Application December 28, 1938, Serial No. 248,093

12 Claims. (Cl. 221—101)

This invention relates to improvement in apparatus for dispensing predetermined quantities of liquids, and will be described in terms of its application in the dispensing of cream, for which it is especially useful.

Objects of the invention are, in a device for the ejection of a predetermined charge of liquid by gravity of the liquid accelerated by the weight of a piston, to provide (a) efficient but simple, inexpensive, and durable means for the predetermination and ejection of such charge; (b) a structure all parts of which are readily accessible for cleaning; (c) improved means for facilitating the manual operation of the device for the ejection of the charge and for the predetermination of the amount thereof.

With these and other objects in view, as will hereinafter more fully appear, the invention comprises certain novel constructions, combinations and arrangements of parts, as will be hereinafter described and claimed and as illustrated in the accompanying drawings in which

Fig. 1 is a central vertical section of the lower portion of a container including the structure comprising this invention, the parts being shown at rest after ejecting a charge.

Fig. 2 is the same as Fig. 1, except that the parts are shown in raised position ready to begin the ejection of the charge.

Fig. 3 is a view like Fig. 1, but showing the complete container and its complete standard and illustrating a modification of the ejecting mechanism adapted for operation by a downward movement of the spout.

Fig. 4 is a fragment of Fig. 3, showing the spout and associated parts at the limit of the down stroke, the piston being shown approximately midway of its down stroke.

Fig. 5 is a fragment, enlarged, of the spout and piston stem and their respective valve seat and valve as embodied in Figs. 1, 2 and 8.

Fig. 6 is a section of line 6—6 of Fig. 5.

Fig. 7 is a fragment of the spout structure in Figs. 3 and 4.

Fig. 8 is the same as Fig. 1, except that it illustrates a modification of the spout operating mechanism.

Fig. 9 is a view partly in plan and partly in section on line 9—9 of Fig. 8.

Fig. 10 is a section on line 10—10 of Fig. 9.

Upon a standard 1, supported uprightly by any suitable means as elongated base 2, I mount a container 3 preferably having an enclosing casting 4 spaced from container 3 for the accommodation of ice, insulation or other material gen-

erally indicated at 5, the whole being connected with and supported upon standard 1 by any suitable bracket indicated at 6.

Container 3 may be as high as, and the upper portion thereof as large in diameter as and of any shape, desired, the diameter of the lower portion being coordinated with the piston and of any size convenient and suitable for the purpose hereinafter described.

The bottom of container 3 is preferably provided with a sump 7 from which depends tubular boss 8 provided with a comparatively large bore 9 in its upper portion and a small bore 10 in its lower portion, the annular beveled shoulder 11 being provided at the point of change in bore.

Piston 12, positioned in said container 3, is made of any suitable material and is of sufficiently smaller diameter than container 3 to allow cream to pass between its edge and the wall of container 3, approximately $\frac{3}{4}$ of an inch clearance being found practical for use in dispensing ordinary cream.

Piston rod or stem 13, fixed centrally to the under side of piston 12, is formed with a plurality of faces 14, the joints 15 between the faces being preferably rounded whereby to afford a freely sliding fit of stem 13 within the large bore 9 of boss 8, the lower end of stem 13 being formed into a valve element 16 preferably by being cone shaped, as illustrated, the co-mating valve element being afforded by the beveled upper end of the bore of spout 17 reciprocally mounted in small bore 10 of the boss 8. But in case of absence of spout 17 or in case the top of the spout is below shoulder 11, then the bevel of shoulder 11 serves as a valve seat. The piston 12 and/or its stem 13 will be formed of material which is heavy by comparison with the specific gravity of the liquid being dispensed, whereby to exert pressure upon the liquid beneath the piston. It will be understood that up to this point the description applies equally to all illustrated embodiments.

In the preferred embodiments illustrated at Figs. 1, 2, 5, 8 and 10, the spout 17 is provided with an annular flange 18 adapted to seat on the shoulder 11 to limit the downward movement of the spout 17, the top of the bore of spout 17 being beveled as at 19, as above mentioned, to form a seat for valve element 16.

In the embodiment illustrated at Figs. 1, 2 and 5, spout 17 is of uniform diameter throughout except for the flange 18 and, in all embodiments, the spout terminates at its lower end in a thin

edge 28 in order to minimize the surface on which liquid can accumulate and cause dripping.

For operation of the piston-valve-spout mechanism above described and illustrated in Figs. 1 and 2, there is provided an annularly channelled operating nut 21 adapted to be set upon the spout 17 by suitable means as by set screw 22. A lever 23, fulcrumed in standard 4, as at 23, engages channel 21' or nut 21, said lever being preferably double so as to engage the channel 21' on both sides of the nut 21 whereby an upward pressure on the outer end of the lever 23 will raise spout 17, stem 13 and piston 12.

To limit the upward stroke of spout 17 and the associated parts above described, adjustable limiting mechanism is provided comprising threaded pin 24 depending from bracket 25 surrounding boss 8 and clamped in position by nut 26 threaded onto boss 8. Adjusting nut 27 is threaded on pin 24 and may be set at any point desired whereby to limit the upward stroke of spout 17 to the point at which nut 21 contacts nut 27 as illustrated in Fig. 2. The length of the stroke determines the size of the charge which will be ejected.

Suitable resilient means 28 are provided for accelerating the downward stroke of lever 23 and spout 17 and associated parts when the upward pressure is removed from the outer end of lever 23.

The operation of the embodiment illustrated in Figs. 1 and 2 is as follows:

Nut 27 is set at the desired point, which can readily be determined by trial ejection of a few charges. It is assumed that a supply of cream is in container 3. Lever 23 is raised by the hand of the operator beneath the outer end of the lever. This raises spout 17, stem 13 and piston 12 to the position shown in Fig. 2, at which time it will be understood that the space in container 3 below piston 12 will be filled with cream which has flowed downwards around the periphery of the piston. The upward pressure is removed from the lever 23, whereupon the weight of the lever 23, nut 21 and spout 17 accelerated by the resilient means 28 will cause the spout and said associated parts to drop practically instantaneously to the position shown in Fig. 1, but the downward movement of the piston 12 and stem 13 will be retarded by the cream beneath the piston, a part of which will pass downwardly through bore 9 along the flat faces 14 of the stem 13 and downwardly through spout 17 while some of the cream will pass upwardly around the periphery of the piston. The downward movement of the piston and of the cream around the piston stem continues until the valve element 16 seats on the valve seat 19, whereupon the flow is instantaneously cut off and the device is ready for a repeat operation. The actual time elapsing between the dropping of spout 17 and associated parts to the lower position as illustrated in Fig. 1, and the end of the down stroke of piston 12 and stem 13, is very small but the interval is still sufficient to permit the predetermined charge of cream to drop from the lower end of spout 17.

Spout 17 has a freely sliding but cream tight fit in bore 10. Flange 18 forms a positive seal when seated on shoulder 11, but there is sufficient clearance between flange 18 and bore 9 to allow any cream which may be beneath flange 18 when it is seating upon the shoulder to pass upwardly around the flange. Otherwise such trapped cream would retard the seating of flange 18 on shoulder 11 and the pressure thereon would tend to force such cream down through bore 10 around

spout 17. Spout 17 is drawn to practically an annular knife edge at the bottom thus eliminating surface for the accumulation of cream with its resulting drip.

In Figs. 3 and 4 there is illustrated a modification of the ejecting mechanism. In this modification the piston, spout and associated parts are held normally in the extreme upward position and the ejection is accomplished by forcing the lever downwardly instead of upwardly. In this embodiment the resilient element 28 is reversed, being placed below the lever 23 so as to force the same upwardly. The nut 21 is reversed so as to bring its flattened face underneath where it will contact nut 27 which is adjusted on pin 24 to limit the downward stroke of lever 23 to the point which will permit the ejection of the desired charge, this point being determined by two or three trial ejections as above described.

The only structural differences between this embodiment and the embodiment illustrated in Figs. 1 and 2 are in spout 17 and the lower end of boss 8. In this embodiment the lower part of spout 17 is enlarged as at 17', the enlargement terminating in a shoulder 17'' for which a seat 8' is provided in the lower end of boss 8. Also in this embodiment the upper end of spout 17 is not provided with the flange 18 but is smooth so that it may be withdrawn through the lower end of boss 8.

In case of such withdrawal of spout 17 while container 3 is charged, valve element 16 will seat on the bevel of shoulder 11 and prevent loss of liquid and it will be understood that the device may be constructed or adjusted so that the upper end of spout 17 will be below shoulder 11 at least a part of the time and that in such case bevelled shoulder 11 will act as a normal valve seat for valve element 16.

To operate this embodiment the lever 23 is pressed downward as rapidly as possible until nut 21 contacts nut 27 stopping the downward motion. As in the other embodiment, the cream below piston 12 retards the downward movement of the piston and stem 13 so that cream flows through bore 9 along the faces of the stem 13 and down through the spout until the piston drops and again seats its valve element 16 in the seat 19 in the upper end of spout 17, or on bevelled shoulder 11 as the case may be, whereupon the flow is cut off as described in connection with the embodiment in Figs. 1 and 2. Thereupon the downward pressure is released from the lever 23 and the resilient element 28 returns the lever 23 and associated parts including the spout 17 and piston 12 with its stem 13 to the extreme upward position as shown in Fig. 3 ready for another operation.

It will be understood that with this embodiment it is possible, in actual operation, to eject a charge less than the predetermined amount by releasing lever 23 before it reaches the limit of the down stroke whereupon spring 28 returns spout 17 to contact with valve element 16 thus stopping the flow prematurely.

The embodiment illustrated in Figs. 8, 9 and 10 operates in the same manner as the embodiment illustrated in Figs. 1 and 2 but in place of the resilient element 28 for accelerating the downward stroke of the lever 23 a weighted handle 29 is provided on the outer end of the lever and a modified structure is provided for forming engagement between the lever 23 and the spout 17, this structure comprising a ring 30 having a rib 31 of triangular cross-section adapted for a slid-

ing fit over spout 17, the spout in this embodiment being provided with an annular groove 32 for the accommodation of pins 33 slidably mounted in ring 31 and slidably engaging the arms 5 of the lever 23. It will be understood that the arms of lever 23 are resilient so that they may be sprung apart for the double purpose of withdrawing their ends 34 from engagement with standard 1 and withdrawing pins 33 from the annular 10 groove 32 whereby to permit the withdrawal of spout 17 from the ring 30.

The lower end of spout 17 is preferably beveled on the outside as at 35 so that it may be inserted in ring 30, wedging apart the pins 33 and permitting the insertion of the spout 17 into the ring 30 in the position shown in Fig. 10, in which position the pins 33 will snap into the annular groove 32 to hold the ring in engagement with the spout 17.

The operation of this embodiment is the same as the above described operation of the embodiment illustrated in Figs. 1 and 2, the upward pressure on the lever being normally applied to the under side of weighted handle 29 which 20 serves to accelerate the downward motion in place of the resilient element 28. At the end of the upward stroke the ring 30 will contact the nut 27 thus limiting the upward stroke.

It will be noted that each embodiment automatically, and without special structure therefor, eliminates suction which would result in drawing air into the liquid while preventing all unintentional flow of liquid out of the container.

While I have illustrated and described many details of construction, it will be understood that various equivalents will occur to those skilled in the art, and I do not wish to be restricted to the details of structure described and illustrated.

I claim:

1. In a liquid dispenser, a container, a piston reciprocable therein, means to permit flow of liquid past the piston within the container, a tubular boss having a larger bore in its upper portion leading downward from the bottom of the container and a smaller bore continuing in alignment with the larger bore and leading therefrom to the lower end of the boss, a stem reciprocable in said larger bore affixed at its upper end to said piston and having a valve element at its lower end, a spout freely reciprocable but with a liquid tight fit within said smaller bore and having in its upper end a valve element co-mating with said stem valve element, and passageway for liquid along said stem within said larger bore.

2. In a liquid dispenser, a container, a piston reciprocable therein, clearance around the piston periphery to permit the flow of liquid therethrough, a tubular boss having a larger bore in its upper portion leading downward from the bottom of the container and a smaller bore continuing in alignment with the larger bore and leading therefrom to the lower end of the boss, a stem reciprocable in said larger bore affixed at its upper end to said piston and having a valve element at its lower end, a spout freely reciprocable but with a liquid tight fit within said smaller bore and having in its upper end a valve element co-mating with said stem valve element, passageway for liquid along said stem within said larger bore.

3. In a liquid dispenser, a container, a piston reciprocable therein, means to permit flow of liquid past the piston within the container, a tubular boss having a larger bore in its upper portion leading downward from the bottom of the con-

tainer and a smaller bore continuing in alignment with the larger bore and leading therefrom to the lower end of the boss, a stem reciprocable in said larger bore affixed at its upper end to said piston and having a valve element at its lower end, a spout freely reciprocable but with a liquid tight fit within said smaller bore and having in its upper end a valve element co-mating with said stem valve element and a co-mating valve element at the upper end of said smaller bore for the seating of said stem-valve-element wherever the upper end of the spout does not intervene.

4. In a structure as defined in claim 1, means for reciprocating the spout and means for predetermination of the quantity of liquid to be ejected comprising a stop limiting the downward movement of the spout, yieldable means adapted to accelerate the downward movement of the spout and to yieldably retain the spout in its lowest position and an adjustable stop limiting the upward movement of the spout.

5. In a structure as defined in claim 1, means for reciprocating the spout and means for predetermination of the quantity of liquid to be ejected comprising a flange on the upper end of the spout for limiting the downward movement of the spout, yieldable means adapted to accelerate the downward movement of the spout and to yieldably retain the spout in its lowest position and an adjustable stop limiting the upward movement of the spout.

6. In a structure as defined in claim 1, means for reciprocating the spout and means for predetermination of the quantity of liquid to be ejected comprising a stop limiting the upward movement of the spout, means adapted to move said spout toward and resiliently hold it in its uppermost position and an adjustable stop limiting the downward movement of the spout.

7. In a structure as defined in claim 1, means for reciprocating the spout and means for predetermination of the quantity of liquid to be ejected comprising a shoulder on the lower part of the spout limiting the upward movement of the spout, means adapted to move said spout toward and resiliently hold it in its uppermost position and an adjustable stop limiting the downward movement of the spout.

8. In a liquid dispenser having a depending reciprocable spout, means for reciprocating the spout and means for predetermining the length of reciprocation thereof comprising a stop limiting the downward movement of the spout, a standard and a weighted lever fulcrumed in the standard and pivotally connected with the spout whereby to afford convenient means for raising the spout and to accelerate the dropping of the spout.

9. In a liquid dispenser having a depending reciprocable spout and a lever for reciprocating the spout, means for pivotally but detachably connecting the lever and the spout comprising a ring having a sliding fit over the spout, an annular groove in the spout, pins reciprocably mounted in opposite sides of said ring and normally projected into said groove, said lever having resilient arms slidably engaging said pins, whereby to retract said pins from said groove by springing apart the said arms.

10. In a liquid dispenser having a depending reciprocable spout and a lever for reciprocating the spout, means for pivotally but detachably connecting the lever and the spout comprising a ring having a sliding fit over the spout, an annular groove in the spout, pins reciprocably and

- rotatably mounted in opposite sides of said ring and normally projected into said groove, said lever having resilient arms slidably engaging said pins, whereby to retract said pins from said groove by springing apart the said arms.
- 5 11. In a liquid dispenser, a vertical container, a depending boss having a bore leading from the bottom of the container to the bottom of the boss, a spout reciprocable in the lower part of the bore and having a liquid tight fit therein and 10 a valve seat at its upper end, a stem reciprocable in the upper part of said bore and having a valve element adapted to fit said seat, passageway for liquid from the container past said stem within said bore and a piston affixed to the upper part 15 of said stem within said container, means to restrictedly permit liquid to pass said piston as it reciprocates within the container whereby to fill the space beneath the piston with liquid for filling the bore and to retard the downward movement of the stem and hold the valve open when the spout is quickly retracted downwardly.
12. In a liquid dispenser having a container with a vertical outlet tube from the container bottom, a spout freely reciprocable but with a liquid tight fit in the lower part of the tube and having a valve seat in its upper end, a plunger reciprocable in said tube above said spout and having a valve element on its lower end whereby 5 the plunger will normally seat on the spout and close the valve and remain in valve-closed position while the spout is stationary or being lifted, passageway along the plunger within the tube for passage of liquid from the container to the valve and means to retard the downward movement of the plunger and open the valve when the spout is dropped. 10 15

THOMAS L. TITUS.
